SPLITTING OPERATION

Richard A. Ruedebush, Belmont, Mass., assignor
to United Shoe Machinery Corporation, Flem-
ington, N. J., a corporation of New Jersey

Application June 15, 1944, Serial No. 540,530

10 Claims. (Cl. 69—21)

This invention relates to a method of treating both tanned and untanned hides and skins to produce splits or hides and skins of uniform thickness. More specifically, the invention relates to a method of treating hides and skins which involves the steps of soaking and unhairing a hide or a skin, smoothing it out with retention of water, freezing it while smooth, and then splitting and/or shaving it while frozen before other steps, which are conventional, are used to produce finished leather. It is to be understood that the method when carried out is not limited to any number or sequence of steps preliminary to the smoothing out step or subsequent to the shaving step and that the tanning step, although usually and preferably introduced before the freezing step, may be undertaken at a later stage.

The object of the invention is to provide an easily controlled and improved method for splitting and/or shaving hides and skins uniformly with the elimination of the customary use and difficulties of a wringer or press.

In the present application when "hides" alone are spoken of, both hides and skins are referred to, the purpose in using the single term being to eliminate verbiage.

The single figure sets forth by way of legends an example of conventional practice in the production of leather and as a comparison therewith an example of the improved practice utilizing the herein-described invention.

In the conventional practice (one illustration thereof is given by the left column of the drawing) the soaked and unhaired hide, which may have been subjected to other preliminary steps such as liming, bating and tanning, is usually split and/or shaved before being converted into finished leather. The operations of splitting and shaving cannot be performed on leather that is soaking wet from the preliminary operations and it therefore becomes necessary to wring or press the excess water out of the leather. The conventional wringing operation is beset with several difficulties. In the first place, the action of a wringer is slow as time must be allowed for the water to exude from the hide. If the wringer speed is increased, the rollers will merely pass over the water leaving the hides substantially as wet as before wringing. The time involved in the wringing operation as well as the skill necessary bring about an appreciable cost for labor. It is also recognized that the cost of mechanical maintenance of a wringer is high, particularly as the wringer felt sleeves must be periodically

replaced. Another important difficulty is that wrinkles in the leather are produced by the wringer and these wrinkles necessitate their removal by adding two more operations—putting-out and shanking. Also, as it is difficult to uniformly exert pressure and remove water from leather, there is a distinct tendency toward a condition of the leather which promotes subsequent uneven splitting. Still another difficulty has been commonly encountered and that is that hides, after passing through a wringer, are usually drier than necessary and that even if they are perfectly wrung out, the usual procedure in a tannery often requires the wrung leather to be held on the tanning floor for a considerable period of time during which the edges become dried out, necessitating wetting back. This difficulty is especially acute in the summer months. The possibility of dry spots developing and the difficulty of wetting back uniformly again bring about a condition which will contribute to non-uniformity of splitting as well as increase the possibility of hide loss because of tearing. After splitting, the leather must still be maintained in a uniform condition in so far as water content is concerned if the subsequent use of dyes is to result in even coloring and high grades of leather. Despite the difficulties of wringing leathers, the use of wringers is preferred to presses for various reasons when conventional practices are used. When a press is used, the hides must be carefully folded to make the pressure uniform. A number of folded hides is piled up on the bed of the press and pressure is slowly increased to permit time for the water to exude without causing damage. After pressing, the hides are tumbled to remove creases and this combination of violent physical actions on the hides is detrimental to the quality of leather ultimately produced. As in the use of a wringer, the use of a press also necessitates wetting back to prevent dry edges.

The method utilizing the present invention is illustrated by means of legends in the right column of the drawing and in this method the use of either a wringer or press is eliminated together with all their difficulties. This method can be used in the case of vegetable tanned leathers but is most useful in producing chrome tanned leathers. Both columns of the drawing may be said to apply in the case of either vegetable or chrome tanned hides. The use of the method is not limited to a time after the tanning operation, as specifically illustrated in the

drawing, but it must be used after the dehairing step, as the presence of hair would cause lumps and make splitting unsatisfactory. The drawing shows six preliminary steps but more or less of these steps can be used. After such preliminary steps as soaking, liming, unhauling, bathing, pickling and tanning there is plenty of water in the hide to make the freezing feasible. Before freezing it is essential that the hide be smoothed out in some way such as by pressure plates, slicking or stretching. Such smoothing out may be done without difficulty and with retention of much of the water. After tanning, and preliminary to freezing, the hides may be hored up for convenience in timing the operations. The hides are then frozen individually while smooth and, after freezing, the hides are not stacked on each other but it is preferable to pass each hide directly through the splitting and/or shaving steps, and by the time an individual hide has reached the coloring step it has thawed out sufficiently for the latter operation. Splitting and/or shaving hides while frozen or semifrozen promotes and assures uniformity of results and at the same time the operator has an effective and easy control.

It should be understood that the splitting operation may be carried out with the type of machines now on the market and that such a machine may be either a belt knife, a reciprocating knife or a fixed knife machine, the main point being that the machine must be so constructed that the frozen splits are not unduly bent while passing through the splitting machine. It is obvious that thin splits are able to withstand more bending than thicker splits without damage.

Some thawing may have taken place when the shaving operation is reached and this will then permit more bending of the splits than would be advisable in the splitting machine. Conventional type shaving machines can be used for the shaving operation, again with increased uniformity and ease of control. Some hides and skins may be shaved without splitting and advantages of the present method are realized in such a case.

After the splitting and/or shaving operations, such conventional steps are then carried out which may be deemed necessary to produce a 50 particular product desired.

Having described my invention, what I claim as new and desire to secure by Letters Patent of the United States is:

1. In a method of treating a hide following such preliminary steps as soaking and unhauling, the steps of smoothing the hide with retention of water, freezing it while smooth, and splitting and shaving it before substantial thawing sets in, such steps being preparatory to subsequent steps necessary to produce leather.

2. Intermediate steps in treating a hide to produce leather comprising soaking, unhauling, smoothing with retention of water, freezing it while smooth, and splitting and shaving before 65 substantial thawing sets in.

3. In a method of producing a chrome tanned hide following such preliminary steps as soaking, unhauling, and chrome tanning, the steps of smoothing the tanned hide with retention of water, freezing it while smooth, splitting and shaving it before substantial thawing sets in, such steps being preparatory to subsequent steps necessary to produce finished chrome tanned leather.
4. In a method of treating hides following such preliminary steps as soaking and unhauling, the steps of hosing up the hides, smoothing each hide individually, freezing it with retention of water while smooth, splitting and shaving it before substantial thawing sets in, and undertaking subsequent steps on the hides necessary to produce leather.
5. In a method of treating a hide following such preliminary steps as soaking and unhauling, the steps of smoothing the hide with retention of water, freezing it while smooth, splitting and shaving it at a temperature which inhibits appreciable thawing, such steps being preparatory to subsequent steps necessary to produce leather.
6. In a method of treating a hide following such preliminary steps as soaking and unhauling, the steps of smoothing the hide with retention of water, freezing it while smooth, and subsequently splitting the frozen hide before substantial thawing sets in.
7. In a method of treating a hide following such preliminary steps as soaking and unhauling, the steps of smoothing the hide with retention of water, freezing it while smooth, immediately splitting the frozen hide and directly shaving it before substantial thawing sets in, such steps being preparatory to subsequent steps necessary to produce leather.
8. In a method of treating hides following such preliminary steps as soaking and unhauling, the steps of hosing up the hides and then passing each hide directly through the steps of smoothing with retention of water, freezing each hide while smooth, splitting and shaving before substantial thawing sets in, such steps being preparatory to subsequent steps necessary to produce leather.
9. In a method of treating a hide to produce leather, following the preliminary steps such as soaking, unhauling and tanning, the intermediate steps of smoothing the hide with retention of water, freezing the hide while smooth, and then splitting the hide before substantial thawing sets in, such steps being preparatory for subsequent steps such as coloring and drying.
10. In a method of treating a hide to produce leather, following the preliminary steps such as soaking, unhauling and tanning, the intermediate steps of smoothing the hide with retention of water, freezing the smoothed hide and then shaving the hide before substantial thawing sets in, such steps being preparatory for subsequent steps such as coloring and drying.
